DESIGN FOR A BED FOOTBOARD

Raymond T. Carlson, Louisville, Ky.

Application June 18, 1934, Serial No. 52,222

Term of patent 14 years

To all whom it may concern:

Be it known that I, Raymond T. Carlson, a citizen of the United States, residing at Louisville, in the county of Jefferson and State of Kentucky, have invented a new, original, and ornamental Design for a Bed Footboard, of which the following is a specification, reference being had to the accompanying drawing, forming part thereof.

The figure is a perspective view of the bed foot-board showing my design; in this figure is shown a headboard, in dotted lines, attached to the bed footboard by a pair of side rails, also in dotted lines, to indicate how the bed footboard is incorporated into a complete bedstead.

I claim:

The ornamental design for a bed footboard as shown and described.

RAYMOND T. CARLSON.
